ARTHUR LINDBLADE, OF BRADFORD, PENNSYLVANIA, ASSIGNOR TO CORLISS CARBON COMPANY, INCORPORATED, OF BRADFORD, PENNSYLVANIA, A CORPORATION OF PENNSYLVANIA.

METHOD OF AND MEANS FOR ATTACHING ELECTRICAL CONDUCTORS TO BRUSHES.

Application filed July 15, 1921. Serial No. 484,846.

To all whom it may concern:

Be it known that I, ARTHUR LINDBLADE, a citizen of the United States, residing in Bradford, county of McKean, and State of Pennsylvania, have invented certain new and useful Improvements in Methods of and Means for Attaching Electrical Conductors to Brushes, of which the following is a specification.

10 This invention relates to methods of and means for securing electrical conductors of the type commonly called pig tails to brushes of the character ordinarily employed for delivering electric currents to, or 15 collecting the same from, the rotating elements of dynamo-electric machinery.

The present invention proposes an improvement on the form of pig tail connections in which the pig tail or cable is secured in an opening in the brush by means of 20 a member inserted in the interior of the cable. This interior member in the prior art ordinarily consisted of a device acting in the manner of an expansion bolt to force the 25 conductors of the cable against the walls of the opening. The devices of this character are composed of hard, unyielding material such as ordinary copper or brass, which by pure outward pressure, is intended 30 to bring about the desired mechanical security and low resistance of contact. It will be readily understood, however, that unless the walls of the opening in the brush and the pig tail itself are very smooth so as to 35 conform closely, there will be contact only at certain high spots, and the true area of contact will be considerably less than the total available area. With smooth walls, on the other hand, the mechanical security will 40 be comparatively low, as the pig tail may be readily pulled out unless an extraordinarily large interior pressure is employed. This pressure, however, is limited because of the tendency of the brushes to fracture under 45 too high a strain.

To obviate these difficulties the present invention proposes the employment of a ma-

terial which will spread laterally when compressive force is applied thereto longitudinally, i. e., in the direction of the axis of the opening. The material will naturally yield most readily at points at which there are crevices between itself and the cable and between the cable and the walls of the opening. The cable therefore will be caused to shape itself accurately to the walls of the opening, and the said material will adapt itself to the interior of the cable, and fill all crevices therein. The net result therefore, of this process is to produce a substantially solid plug consisting of the end of the cable completely filled with the material, the exterior shape of this plug being the same as the shape of the opening. To enhance the mechanical security of the connection the walls of the opening are preferably provided with recesses into which the strands of the cable will be forced, thus incidentally increasing the actual area of contact. The present invention thus not only renders it possible to obtain a large area of actual contact and low contact resistance without the employment of excessive force, but it provides for enhanced mechanical security without the loss of area of contact.

A good understanding of the invention may now be had from the following description of one manner of practicing the same, and one form of embodiment thereof, reference being had to the accompanying drawing, in which,

Figure 1 illustrates the manner in which the connection is made;

Figure 2 shows one form of insert for use in this invention; and

Figure 3 illustrates the finished connection.

Similar characters of reference designate similar parts in each of the several views.

In accordance with the present invention, the brush B is provided with an opening such as 1, slightly larger than the diameter of the pig tail 2 which is to be secured to the

brush. The side walls of opening 1 are preferably provided with annular recesses such as 3 for the purpose of enhancing the security of the mechanical connection, as 5 will be explained hereinafter.

The pig tail, which is preferably in the form of a stranded cable, is introduced into opening 1, so that the ends of the conductors thereof engage the bottom wall of the opening. At a point just above the opening the cable is slightly opened or twisted apart so that a plug 4 may be inserted into the interior of the cable.

This plug is preferably slightly pointed 15 as shown and made up preferably of a composition consisting of about 80 per cent copper, 15 per cent lead and 5 per cent graphite, these materials being combined into a solid composition by any suitable 20 process, as for example, by mixing the materials in powder form, the copper being preferably approximately 200 mesh and the lead having a substantially equal or even greater fineness. This mixture is compressed 25 in dies of suitable form under a pressure of several tons per square inch—sufficient to cause the material to hold firmly together. These pieces are baked in a reducing atmosphere until a temperature of approximately 1500° F. has been attained. The material thus produced is solid 30 in form, has good mechanical strength, low electrical resistance and possesses such malleability as to flow or yield laterally when subjected to compressive force, particularly 35 hammered by hand or by an automatic device such as the well known oscillatory punch. Such a device applies the blows comparatively lightly and in rapid succession, thus saving time and minimizing any tendency of cracking or other breach of continuity of the material of which the member 4 is composed.

The plug is then hammered downwardly 45 toward the bottom of the opening, this operation being continued until the material of the plug yields to the compressive forces and flows laterally to enter the crevices of the cable, forcing the strands thereof into 50 intimate engagement with the walls of the opening, and causing the same to enter the recesses 3. The end of the cable and the member 4 are thus united into a substantially solid plug devoid of internal crevices 55 and having therefore high electrical conductivity. The shape of the plug, moreover, conforms to the shape of the opening, so that there is a large area of contact and low contact resistance, as well as mechanical 60 security.

Although the material with which the interior of the cable is filled is described as consisting preferably of a solid plug of malleable material, it will be understood 65 that the invention is not limited thereto, and

that in fact any material may be employed which will yield as above described so as to give the desired result.

Many other changes and modifications may be made without departing from the 70 spirit and scope of the invention, it being intended to claim the same broadly in whatever form its principles may be employed.

What I claim is:

1. The method of securing a pigtail in 75 an opening of a brush which consists in inserting the end of the pigtail in the opening, introducing a member of malleable material within the central portion of the pigtail, and subjecting said member to longitudinal compressive force so as to bring about lateral flow of the material of said member, whereby said pigtail is forced into intimate engagement with the walls of said opening.

2. The method of securing a stranded cable in an opening of a brush, which consists in recessing the side of the opening, introducing the end of the cable in the opening, and subjecting a member of malleable 80 material in the interior of the cable to longitudinal compressive force to cause its lateral expansion, whereby the strands of said cable are forced into the said recesses and the said member is forced into the interior 85 recesses of the said strands.

3. In combination, a brush provided with an opening having recessed side walls, a conductor cable for said brush, said cable having one end in said opening, and means 100 interior to said cable and compressed to conform to the internal irregularities of the cable, whereby the strands of the cable are compressed against the walls of said opening and caused to enter the recesses in 105 said side walls.

4. The method of securing a conductor in an opening in a brush, which consists in inserting the end of said conductor in the opening, filling the interior of said conductor with conductive material and subjecting said material to compressive force, so as to cause the said material to adapt 110 itself to the crevices of said conductor and force the same into intimate engagement 115 with the wall of the opening of the brush.

5. In combination, a brush provided with an opening having recessed sidewalls, a conductor cable for said brush, said cable having one end in said opening, and a plug 120 of metal graphite composition interior to said cable and compressed to retain said cable within said opening.

6. In combination, a brush provided with an opening having recessed sidewalls, a conductor for said brush, and a compressed plug of metal graphite composition interior to said conductor for retaining said conductor in said brush.

7. The method of securing a stranded 125

conductor in an opening in a brush, which consists in inserting the end portion of said conductor into the opening, opening the strands of the conductor at a point above the portion of the conductor inserted within the opening, and introducing a member of malleable conducted material into the interior of the conductor and subjecting

said member to compressive force so as to cause the said member to adapt itself to the crevices of the said conductor and force the same into intimate engagement with the wall of the opening of the brush.

In testimony whereof I have affixed my signature to this specification.

ARTHUR LINDBLADE.
